UNITED STATES PATENT OFFICE.

AUGUST W. L. HARTBAUER, OF CHICAGO, ILLINOIS, ASSIGNOR TO AMERICAN CAR AND FOUNDRY COMPANY, OF ST. LOUIS, MISSOURI, A CORPORATION OF NEW JERSEY.

RAILWAY-CAR-DECK VENTILATOR.

1,199,786.

Specification of Letters Patent.

Patented Oct. 3, 1916.

Application filed October 1, 1912. Serial No. 723,439.

To all whom it may concern:

Be it known that I, AUGUST W. L. HARTBAUER, a citizen of the United States, residing at Chicago, Illinois, have invented a certain new and useful Improvement in Railway-Car-Deck Ventilators, of which the following is a full, clear, and exact description, such as will enable others skilled in the art to which it appertains to make and use the same, reference being had to the accompanying drawings, forming part of this specification, in which—

Figure 1 is a perspective view of a portion of a railway car deck with my improved ventilator positioned thereon. Fig. 2 is a horizontal section taken approximately on the line 2—2 of Fig. 1. Fig. 3 is a vertical section taken approximately on the line 3—3 of Fig. 1. Fig. 4 is a perspective view of a portion of a railway car deck, and showing a modified form of the ventilator. Fig. 5 is a vertical section taken approximately on the line 5—5 of Fig. 4. Fig. 6 is a horizontal section taken approximately on the line 6—6 of Fig. 5. Fig. 7 is a perspective view of a portion of a railway car deck, and showing a further modified form of the ventilator.

This invention relates to new and useful improvements in ventilators particularly intended for use on the decks of railway passenger cars, the principal object of my invention being to arrange on the side of the car deck a simple, inexpensive ventilator having communication with the interior of the car, and which ventilator is provided with one or more curved or inclined faces against which wind or the air encountered during the movement of the car and its ventilators impinge, and which curved or inclined faces deflect the wind or air at points near the exit opening of the ventilator, thereby creating a suction of air from the interior of the car through the ventilator.

A further object of my invention is to construct a deck ventilator with the exit opening at the bottom and to provide means on the ventilator adjacent to said exit opening for effectually preventing rain, snow, cinders, dust and like foreign substances from entering the exit opening and passing therethrough to the interior of the car.

A further object of my invention is to

provide a deck ventilator through which a suction of air is produced without adjustment of any parts, regardless of the direction in which the car is moving, and further to produce a ventilator which can be cheaply manufactured, and which presents a neat and finished appearance when applied for use.

To the above purposes my invention consists in certain novel features of construction and arrangement of parts hereinafter more fully described and claimed.

Referring by numerals to the accompanying drawings, and particularly to the form of ventilator illustrated in Figs. 1 to 3 inclusive, 1 designates the car deck, 2 the deck posts, 3 an opening between the posts 4 an ordinary form of slotted register located on the interior of the car immediately over the opening 3. Applied to the exterior of the deck immediately over the opening 3 is a plate 5, preferably of metal, and formed therein is an opening 6. Fixed to this plate at the sides of the opening 6 is a pair of outwardly extending parallel walls 7, the outer ends of which are bent outwardly away from each other to form a pair of vertically disposed front walls 8, which are parallel with the base plate 5. Vertically disposed, longitudinally curved walls 9 extend from points near the ends of the base plate 5 to points on the walls 7 immediately to the rear of the front walls 8, and positioned between the outer ends of these curved walls and the ends of the front walls 8 are vertically disposed deflecting walls or plates 10, which occupy planes at angles of approximately 45 degrees relative to the planes occupied by the front walls 8 and base plate 5. These deflecting walls or plates 10 are comparatively narrow and are arranged so as to deflect the currents of air away from the mouth of the opening 6, thus preventing any tendency of the air after passing over the surfaces of the curved walls 9 to enter the mouth of the opening 6, thereby setting up back drafts to interfere with or reduce the suction of foul air through said opening. Fixed in any suitable manner to the upper and lower edges of the walls 7, 8, 9 and 10 are horizontally disposed top and bottom plates 11 and 12. When this par-

ticular form of ventilator is in service and the car upon which said ventilator is mounted is in motion the air encountered by the forward one of the curved plates or walls 9 is deflected outwardly as shown by arrows in Fig. 2, and the air thus encountered striking against the corresponding angular wall or plate 10 will be deflected outwardly, as shown by arrows immediately in front 10 of and adjacent to the vertically disposed exit opening between the forward ends of the walls 7. This rapid and forceful passage of air across the exit opening of the ventilator naturally creates a draft or suction of air through the ventilator, and thus 15 air from the interior of the car is drawn through the register 4 into the opening 3, from whence said air discharges outwardly through the opening between the walls 7.

20 It will be noted that the walls or plates which are very narrow are located very close to the mouth of the opening 6, and these plates are arranged so as to direct the air from the curved surfaces of the walls 10 25 outwardly at an angle relative to the front wall 8 in which the mouth of the opening 6 is formed, and this arrangement prevents the formation of back drafts through said opening.

30 By providing the curved plates 9 on both sides of the ventilator the device is adapted to create a suction of air from the interior of the car through the ventilator as the car is moved in either direction.

35 It will be readily understood that when a car equipped with my improved ventilator is at rest or is moving at a very slow speed, wind which may be blowing in a direction lengthwise of the car will impinge against 40 either one of the curved plates 9, thereby creating suction through the ventilator to draw air from the interior of the car. The draft of air from the interior of the car can be readily regulated by a proper manipulation 45 of the register 4.

In the modified construction illustrated in Figs. 4 to 6 inclusive the main body of the ventilator comprises a box-like structure 13 provided with an extension 14 which communicates with the interior of the car, and in this form of device the exit opening is located at the bottom of the structure 13. Extending downwardly and outwardly from the top of the structure 13 at both ends 50 and at the outer side are inclined plates 15, and positioned between the lower ends of these plates and the corresponding lower ends of the end and outside walls of the structure 13 are curved plates 16. Extending 55 outwardly and downwardly from the lower ends of these curved plates 16 are comparatively narrow deflector plates 17 which are arranged at angles of approximately 45 degrees relative to a vertical plane. In this form of device a screen of

section of wire netting 18 is located in the exit opening at the lower end of the structure 13, and if desired a series of inclined deflector plates 18^a may be arranged beneath this screen, thereby preventing rain, snow, 70 cinders and the like from entering the ventilator. The action and operation of this form of ventilator is identically the same as the action and operation of the form of ventilator previously described, and in addition this second form of ventilator has the advantage of producing a suction of air from the interior of the car while said car is standing still, and wind from any one of three directions impinges against the inclined plates 16.

In the modified construction of the ventilator seen in Fig. 7 the main body of the ventilator is surrounded by a semi-circular shell 19 having an inwardly and downwardly curved face 20 from the lower edge of which projects outwardly and downwardly an inclined deflecting member 21. In this form of device air or wind striking against the curved surface 20 is deflected 85 downwardly, thence outwardly by the deflecting flange or member 21, thereby setting up a suction of air through the ventilator.

A ventilator of my improved construction 90 is very compact, presents a neat and finished appearance when applied for use, can be manufactured at comparatively little cost, and in service is very effective in drawing air from the interior of the car to which it is attached.

It will be readily understood that minor changes in the size, form and construction of the various parts of my improved ventilator can be made and substituted for those 95 herein shown and described without departing from the spirit of my invention, the scope of which is set forth in the appended claims.

I claim:

1. A railway car deck ventilator comprising a housing adapted to be positioned upon a railway car deck, which housing is provided with inlet and outlet openings, said housing having one of its walls formed so as 110 to produce an exteriorly arranged concave surface, one end of which terminates adjacent to the outlet opening of the housing, and a comparatively narrow deflector plate positioned between the end of the concave 115 surface and the exit opening, which plate is inclined away from the outlet opening as it extends outwardly from the car.

2. A railway car deck ventilator comprising a housing having air inlet and outlet 120 openings, said housing being provided with an outwardly presented curved ramming surface, one end of which terminates adjacent to the exit opening of the housing 125 and said housing being provided with a sub- 130

stantially flat air deflecting surface, the same being arranged between the end of the curved ramming surface and the exit opening of the housing and said flat surface being inclined away from the outlet opening as it extends outwardly from the car to which the ventilator is attached.

In testimony whereof I hereunto affix my signature in the presence of two witnesses, this 18th day of September, 1912.

AUGUST W. L. HARTBAUER.

Witnesses:

DONALD D. MILLIKIN,
C. W. RUDOLPH.
